(57) CLAIM

The ornamental design for a handbag, as shown and described.

DESCRIPTION

FIG. 1 shows a top, front right side perspective view of the handbag;

FIG. 2 shows a back elevational view of the handbag;

FIG. 3 shows a front elevational view of the handbag;

FIG. 4 shows a top plan view of the handbag;

FIG. 5 shows a bottom plan view of the handbag; and,

FIG. 6 shows a right side elevational view of the handbag, the left side elevational view being identical thereto.

The broken lines showing a set of handle straps are for the purposes of illustrating environment and form no part of the claimed design.
